UNITED STATES PATENT OFFICE.

CLARENCE E. PRATT, OF DALLAS, TEXAS.

ENGINE.

1,306,717.

Specification of Letters Patent. Patented June 17, 1919.

Application filed September 25, 1916. Serial No. 121,932.

To all whom it may concern:

Be it known that I, CLARENCE E. PRATT, citizen of the United States, residing at Dallas, in the county of Dallas and State of Texas, have invented a certain new and useful Improvement in Engines, of which the following is a full, clear, concise, and exact description, reference being had to the accompanying drawings, forming a part of

10 this specification.

My invention relates to engines which employ governors having inertia bars or governing weights and, in one characteristic of the invention, the inertia bars constitute 15 parts of counterweights that are provided to counterbalance engine cranks. In accordance with another feature of the invention the inertia bars are caused to operate in oil chambers that are in the nature of 20 dash pots to cushion the movements of the governor parts.

These and other features of my construction will be fully set forth by reference to the accompanying drawings showing the 25 preferred embodiment thereof and in which Figure 1 is a side view, partially in section, of an engine equipped in accordance with the invention; Fig. 2 is a sectional view on line 2 2 of Fig. 4; Fig. 3 is a sectional view 30 on line 3 3 of Fig. 4; Fig. 4 is a sectional view on line 4 4 of Fig. 5; and Fig. 5 is a sectional view on line 5 5 of Fig. 4.

Like parts are indicated by similar characters of reference throughout the different 35 figures.

The engine illustrated is of the type disclosed and claimed in my co-pending application Serial No. 62,692, filed November 22, 1915, but the invention is not to be 40 limited in its application to engines of that type. This engine is a high speed self-oiling steam engine whose base 1 supports the engine frame 2 at whose forward end there is carried the usual engine cylinder 3 and 45 valve chest 4, while at whose rear end there is provided a bearing 5 in which the main engine shaft 6 is turned. The piston within the cylinder 3 has the usual piston rods 7 in connection with the crosshead 8, the 50 crosshead having the usual connection with one end of a pitman 9 whose other end is connected with a crank pin 10. This crank pin is mounted upon a crank 11 which is in fixed relation with the shaft 6, the crank being 55 desirably formed integrally with the shaft and having an integral continuation

12 upon the other side of the shaft diametrically opposite the crank to constitute a portion of the counterweight for the crank. The counterweight 12 is desirably in the 60 form of a segment of a circle concentric with the shaft, this counterweight dipping within the oil that is provided in the bottom of the crank case 13 in which the governor is disposed for the purpose of splashing oil 65 and casting it forwardly to oil the crosshead and other parts of the engine at the cylinder end thereof and to deposit oil upon other bearings, there being provision for returning the oil to the crank case so that it may be 70 used over and over again as is well understood by those familiar with the art. The oil in the crank case is desirably maintained at a sufficient depth to enable the outer end of the crank arm 11 also to dip into the oil 75 on each revolution of the engine shaft whereby the crank pin is thoroughly lubricated.

The counterweight 12 is cast with a slot or opening 14 therein which is of such shape 80 as to accommodate the inertia bar or governing weight 15 throughout the range of movement of such inertia bar. This slot also has an enlargement 16 to accommodate the attachment 17 that unites the inertia bar with the governor spring 18, the inertia bar having several pockets 19 located at different distances from the pivot 20 of the inertia bar whereby the spring may be adjusted in its connection with the 90 inertia bar toward or from its pivot. A peripheral band 21 is concentric with the shaft 6 and is bolted to the counterweight 12 to close the slot or opening 14 at the periphery of the counterweight whereby the 95 slot also forms an oil containing pocket to which oil is transferred from the bottom of the crank case when the counterweight 12 passes through the oil. The oil in the pocket 14 operates to retard the movement 100 of the inertia bar and the governor parts connected therewith. The crank arm 11 has cast integrally therewith webs 22, 23 carrying an arcal bridge 24 that is concentric with the engine shaft 6 and to which the 105 band 21 is bolted. The spring 18 is anchored to the web or anchorage 22 at 22' as indicated clearly in Fig. 4.

The valve rod 25 is pivotally connected with the upper end of a rocker arm 26 intermediately pivoted at 27 upon and within 110 an enlargement of the engine case, as fully

set forth in my said co-pending application, the mounting for the rocker arm being in a position to be reached by some of the oil which is cast upwardly by the counterweight 5 12 and the crank arm 11. The lower part of the rocker arm is pivotally connected with one end of the reach rod 28, the other end of this reach rod being pivotally connected with one arm 29 of a bell crank lever on the 10 back side of the crank pin, this bell crank lever including in its formation an elbow shaft 30 that passes through the crank and crank pin 10 to the other arm 31 of the bell crank lever. This latter arm of the bell crank is connected by a link 32 with the inertia bar 15. The reach rod operates in a vertical plane parallel with the plane in which the pitman 9 operates, this rod and its connections with the rocker arm and inertia bar being located within the engine case so as to be reached by oil or other lubricant which is cast upwardly by the rotating parts 20 within the crank case.

The operation of the governor will be well understood without further explanation, while the advantages of disposing the inertia bar within the counterweight will be readily appreciated by those familiar with the art, one of these advantages residing in 25 making the inertia bar a supplement to the counterweight thereby lessening the aggregate weight of the inertia bar and counterweight for the crank arm while at the same time provision may be afforded in the counterweight element that is integral with the crank shaft to contain some retarding means such as liquid (preferably oil from the crank pit) for checking the movement of the inertia bar and other governor parts. My improved connection of the inertia bar with the reach rod through the crank pin is also of much advantage in construction, assembly 30 and operation as is also the means by which the governor spring is anchored.

45 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A steam engine including an engine 50 shaft, a crank associated with said shaft and including a crank pin, a shaft extending through the crank pin eccentric to the latter, a valve mechanism, a reach rod connected to the valve mechanism and operatively connected to one end of the second shaft, and a governor operatively connected to the other end of the second shaft.

2. The combination with an engine governor having a governing weight; of an engine crank; and a counterweight for the 55

crank at which the governing weight is located to constitute a supplement to the counterweight.

3. The combination with an engine governor having a governing weight; of an engine crank; and a counterweight for the crank to which the governing weight is attached to constitute a supplement to the counterweight.

4. The combination with an engine governor having a governing weight; of an engine crank; and a counterweight for the crank at which the governing weight is located to constitute a supplement to the counterweight, the counterweight having a liquid receiving pocket in which the governing weight operates and in which liquid may be disposed to retard movement of the governing weight.

5. The combination with an engine governor having a governing weight; of an engine crank; and a counterweight for the crank to which the governing weight is attached to constitute a supplement to the counterweight, the counterweight having a liquid receiving pocket in which the governing weight operates and in which liquid may be disposed to retard movement of the governing weight.

6. The combination with an engine governor having a governing weight; of an engine crank; a counterweight for the crank at which the governing weight is located to constitute a supplement to the counterweight; and means provided in connection with the counterweight for retarding movement of the governing weight.

7. The combination with an engine governor having a governing weight; of an engine crank; a counterweight for the crank to which the governing weight is attached to constitute a supplement to the counterweight; and means provided in connection with the counterweight for retarding movement of the governing weight.

8. The combination with an engine governor; of an engine crank; a reach rod upon one side of the crank; a crank pin carried by the crank; a bell crank having one arm connected with the reach rod and including an elbow shaft passing through the crank pin and crank, the other bell crank arm being upon the other side of the crank; and a link connecting this latter bell crank arm with the governor.

9. The combination with an engine governor; of an engine crank; a reach rod upon one side of the crank; a bell crank having one arm connected with the reach rod and including an elbow shaft passing through the crank, the other bell crank arm being upon the other side of the crank; and a link connecting this latter bell crank arm with the governor.

10. The combination with an engine gov-

ernor; of an engine crank; a reach rod upon one side of the crank; a bell crank having one arm on one side of the crank and connected with the reach rod and its other arm upon the other side of the crank; and a link connecting this latter bell crank arm with the governor.

In witness whereof, I hereunto subscribe my name this 19th day of Sept. A. D. 1916.

CLARENCE E. PRATT.
